REFRIGERATING APPARATUS

John Karmazin, Huntington, Ind., assignor to
General Motors Corporation, Dayton, Ohio, a
corporation of Delaware

Application September 30, 1936, Serial No. 103,277

7 Claims. (Cl. 62—126)

This invention relates to refrigeration and particularly the cooling elements for refrigerating systems.

An object of my invention is to provide an improved cooling element of pressed sheet metal construction.

Another object of my invention is to unidirectionally assemble a plurality of similar pressed sheet metal members together and to bond the members to one another to form a cooling element having a plurality of refrigerant passages therein and integral fin members extending from the walls of the passages.

A further object of my invention is to provide a cooling element of pressed sheet metal construction having refrigerant passages therein and improved means for stiffening the element and for distributing incoming refrigerant at a plurality of points throughout the length of the passages.

In carrying out the foregoing objects it is a still further and more specific object of the invention to provide a cooling element with means for distributing incoming refrigerant to a plurality of points throughout its refrigerant passages and to provide means for causing a recirculation of refrigerant from one part to other parts of the element to thereby increase the efficiency thereof.

Further objects and advantages of the present invention will be apparent from the following description, reference being had to the accompanying drawings, wherein a preferred form of the present invention is clearly shown.

In the drawings:

Fig. 1 is a side elevational view of a cooling element constructed in accordance with the present invention;

Fig. 2 is an end view of the cooling element disclosed in Fig. 1;

Fig. 3 is an enlarged side view taken in the direction of the lines 3—3 in Fig. 2 showing the cooling element partly in section and partly in elevation;

Fig. 4 is a horizontal fragmentary enlarged section taken on the line 4—4 of Fig. 3 showing the support of a refrigerant pipe within another refrigerant pipe;

Fig. 5 is a vertical fragmentary enlarged section taken on the line 5—5 of Fig. 3 and further showing the support of a refrigerant pipe within another refrigerant pipe;

Fig. 6 is a top plan view of a portion of the small refrigerant pipe;

Fig. 7 is an end view of the refrigerant pipe disclosed in Fig. 6;

Fig. 8 is an enlarged sectional view of the refrigerant inlet connection of the cooling element and is taken on the line 8—8 of Fig. 3;

Fig. 9 is a fragmentary side view of a modified form of cooling element having fins of a different design; and

Fig. 10 is a vertical sectional view of the modified cooling element design showing the fin contour.

Referring to the drawings, for the purpose of illustration, I have shown in Fig. 1 thereof a cooling element or evaporator generally represented by the reference character 11. Cooling element or evaporator 11 is provided with a liquid refrigerant inlet connection 12 and a gaseous refrigerant outlet connection 13 adapted to be connected by suitable pipes with any conventional refrigerant liquefying and circulating unit (not shown). The cooling element or evaporator 11 is constructed of a plurality of unidirectionally superimposed sheet metal fin members 14 each having a plurality of tube elements 15 struck or pressed therefrom and telescoped together to provide a plurality of parallel and horizontally disposed rows of closed refrigerant conduits or passages 16 extending through the structure and disposed in vertical rows. In striking each of the tube elements 15 from the fin members 14 an opening 17 (see Figs. 4 and 5) is punched from the sheet metal at the small diametered end of the tube elements 15. The material adjacent the opening 17, at the small diametered end of the tube elements 15, is cut and deformed as at 18 to provide a perforated wall comprising a vertical part 19 and two horizontal parts 21 and 22 (see Figs. 4 and 5) extending across the refrigerant passages 16 formed by the superimposed and telescoped together tube elements 15. The plurality of openings 17 and the wall parts 19, 21 and 22 provided in the fin members 14 are for a purpose to be presently described.

After stacking a predetermined number of the fin members 14 upon one another with the tube elements 15 thereof in registration or telescoped relation to form a cooling element of a certain size, a plurality of small plate members 25 (see Fig. 3) having a pair of tube elements 26 formed therefrom are placed against the element 11 at one end thereof. One of the pair of tube elements 26 of plate members 25 registers and communicates with a lower refrigerant passage 16 of a horizontal row thereof while the other of the pair of tube elements 26 registers and communicates with an upper refrigerant passage 16. A cap or end cover 27 is secured to the edge of each of the

end plate members 25 and provide closed U-bends communicating with each pair of vertically arranged refrigerant passages 16. A bracket 28 is then welded or otherwise secured to each of the 5 vertically disposed caps 27 for supporting the cooling element 11 in a vertical position.

It will be noted that the two fin members 14 adjacent the opposite or right hand end of the structure as viewed in Fig. 3 have the entire vertical end portion of the tube elements 15 cut away to provide clearance for the insertion of stiffening members which in the present invention are in the form of small pipes 31 into the refrigerant passages 16. A plate 32 forming one 10 wall of a header 33, is provided with flanged openings 34 which are secured to the tube elements 15 of the fin members 14 at this opposite end of the structure. A corrugated plate 35, forming the other wall of header 33, is secured 15 in any suitable manner to plate 32. The refrigerant passages 16 formed by the telescoped tube elements 15 communicate with the interconnected passages of header 33 formed by the corrugations in plate 35. Plate 35 is also provided with a plurality of flanged openings 36 which are disposed 20 in alignment with the openings 17 provided in the perforated cross wall part 19 at the ends of the tube elements 15. One end of the small pipes 31 is adapted to be secured in the flanged openings 36 of corrugated plate 35. A second corrugated plate 38, having interconnected passages 39, is secured to the corrugated plate 35. The liquid refrigerant inlet connection coupling 12 is secured to a central enlarged portion 41 formed in 25 plate 38. It will be noted that the plate 32 and the first corrugated plate 35 each also have an enlarged portion registering and forming a chamber 42 at the upper portion of the evaporator 11. Chamber 42 communicates with the gaseous refrigerant outlet connection 13 and serves as an 30 equalizing chamber during operation of the refrigerant liquefying and circulating unit connected to the evaporator.

A conduit 45 has its one end 46 secured to an opening provided in plate 35 to thereby communicate with the header 33 and has its other end 47 secured to an opening in the liquid refrigerant inlet connection coupling 12. By referring to Fig. 8 of the drawings it will be noted that the end 47 of conduit 45 is cut at an angle as at 48 so as to dispose a portion of the end 48 of conduit 45 in the path of liquid refrigerant flowing into the evaporator 11. The portion 48 of conduit 45 obstructs the flow of liquid refrigerant to the evaporator and this obstruction causes a suction to be created in conduit 45 to thereby draw liquid refrigerant from the lower part of header 33 and causes its flow upwardly in conduit 45 to the chamber 41. The conduit 45 and its arrangement in connection 12 thereby causes a recirculation of liquid refrigerant from one part to other parts of the evaporator 11 and greatly increases the efficiency thereof. While I have found that the structure shown will provide sufficient suction pressure in conduit 45 for the purpose disclosed this suction pressure may, if desired, be increased by providing a conventional venturi arrangement as is well known to those skilled in the art.

70 By referring to Figs. 6 and 7 of the drawings it will be observed that the pipe 31, which is inserted in the openings 17 of cross wall parts 18, 19, 21 and 22 at the end of tube elements 15 in fin members 14, has a rounded end portion 51 and a flattened portion 52 which provides a

conduit of elongated contour in cross-section. By locating pipes 31 in the refrigerant passages 16 the evaporator is stiffened and the structural strength thereof is thereby increased. The ends 51 of pipes 31 are secured to the flanged openings 36 of plate 35 and the pipes 31 extend continuously through the refrigerant passages 16 and terminate in the end cups 27 at the one end of the evaporator 11. The stiffening members or pipes 31 are firmly supported in spaced relation to the walls of passages 16 by the cross wall parts 18, 19, 21 and 22 at the ends of the tube elements 15. The flattened portion 52 of pipes 31 have a crevice 53 provided in any suitable manner therein and extending from a point adjacent the round end portion 51 thereof throughout the remainder of their length. The opening provided by the crevice 53 and leading into the passage 16 is intermittently interrupted or closed by the plurality of cross wall parts 21 which lie against 20 and are secured to the pipes 31. These pipes 31 serve to distribute liquid refrigerant, flowing into the evaporator 11 from header passage 39, at a plurality of points along the length of the passages 16 formed by the tube elements 15 in a 25 manner and for a purpose to be hereinafter described.

In Figs. 9 and 10 I have shown my invention incorporated in an evaporator structure wherein the fin members 61 are complementary 30 parts of other fin members 62. In this form of my invention the two fin members 61 and 62 together with their respective side web portions 63 and 64 are cut or stamped from a piece of metal substantially of a size ordinarily employed 35 to provide a single fin as is fully disclosed in the patent to Jesse G. King No. 2,055,499 dated Sept. 29, 1935. The inactive fin portion of an ordinary fin is thereby utilized to form a second fin which greatly reduces the amount of material necessary 40 to provide the required number of fins on an improved evaporator of the type disclosed.

It is to be noted that the tube elements 15 of fin members 14 may be secured at the same time pipes 31 are secured to plate 35 and to cross wall parts 18, 19, 21 and 22 by brazing or soldering in any manner well known to those skilled in the art in accordance with the steps of assembly employed. All the parts and elements of the improved evaporator disclosed are firmly secured together to provide a unitary structure. The pipes 31 serve to stiffen and increase the structural strength of the evaporator disclosed. The unitary structure has an improved refrigerant flow circuit embodied therein to thus increase the efficiency thereof as will be apparent from the detailed description of the flow of refrigerant through the evaporator.

Liquid refrigerant flows from an expansion or float valve employed in a closed refrigerating system, with which evaporator 11 is a part, into the inlet connection 12 of evaporator 11. This liquid refrigerant enters the chamber 41 and is directed by the header passages 39 formed in plate 38 to the open ends 51 of the plurality of pipes 31. The liquid refrigerant flows through the pipes 31 and is distributed at a plurality of spaced points, through the crevices 53, into the refrigerant passages 16, formed by the tube elements 15 provided on fin members 14. Distribution of liquid refrigerant in this manner occurs simultaneously over substantially the entire evaporator and causes agitation of refrigerant contained therein to thereby create a disturbance of the refrigerant in the evaporator to thus stimulate evapo- 71

ration or vaporization. The expansion or float valve and other elements of the refrigerating system are constructed and arranged to maintain a predetermined level of liquid refrigerant in the evaporator 11. To further stimulate vaporization or boiling of refrigerant in the cooling element or evaporator 11 the conduit 45, by virtue of the suction created therein by the velocity of incoming liquid refrigerant to the evaporator, causes a recirculation of liquid refrigerant from one part of the evaporator to other parts thereof. Liquid refrigerant drawn by conduit 45 from the lower portion of evaporator 11 comes with the relatively cold incoming liquid refrigerant and thereby quickly increases the temperature of liquid refrigerant flowing through pipes 31 to further stimulate boiling. The distribution of liquid refrigerant at a plurality of points into the refrigerant passages 16 and the recirculation of liquid refrigerant from the lower part of evaporator 11 by the conduit 45 to a plurality of other parts thereof prevents the formation of quiet or dormant zones within the evaporator. By eliminating the presence of such zones the transfer of heat from the fluid to be cooled by the evaporator to refrigerant contained therein is greatly increased. The fin members 14 also aid in transferring this heat to thereby provide an evaporator of maximum efficiency. Refrigerant vaporized in the refrigerant passages 16 of evaporator 11 flows therefrom into the header passages 33 and upwardly therein to the gaseous refrigerant chamber 42 from where it is drawn by suction of the refrigerant liquefying and circulating unit through outlet connection 13. From the foregoing it will be seen that I have provided an improved unitary evaporator or cooling element for a refrigerating system which can be constructed from a plurality of unidirectionally nested and secured together sheet metal integral fin and tube members. The improved distribution into and recirculation of liquid refrigerant in the evaporator as described and the integral fin and tube elements, together with the integral cross wall parts extending into the refrigerant passages forms a structure which provides maximum and efficient heat transfer from a fluid to be cooled to refrigerant in the evaporator while at the same time providing a structure that can be readily manufactured at low cost.

While the form of embodiment of the invention as herein disclosed, constitutes a preferred form, it is to be understood that other forms might be adopted, all coming within the scope of the claims which follow.

What is claimed is as follows:

1. A cooling element for a refrigerating system comprising in combination, a plurality of metal fin members each having a tube portion extending therefrom, said fin members being superimposed one upon the other with the tube portions thereof telescoped and secured together to provide a closed refrigerant passage extending through the element, a pipe disposed within said refrigerant passage, said pipe having a crevice in its top surface and extending substantially throughout the length of the pipe, means formed integral with the tube portions of said fin members for supporting said pipe in spaced relation to the walls of said refrigerant passage, and said means cooperating with the crevice in said pipe to provide a plurality of spaced apart openings throughout the length of said pipe for discharging liquid refrigerant into said refrigerant passage at a plurality of spaced points.

2. A cooling element for a refrigerating system comprising in combination, a plurality of fin members having a plurality of tube portions extending therefrom, said fin members being superimposed one upon the other with the tube portions thereof telescoped and secured together to provide a unitary structure having a plurality of rows of closed refrigerant passages extending through the structure, a pipe disposed within one of said plurality of refrigerant passages, said pipe having a crevice in its top surface and extending substantially throughout the length of the pipe, means formed integral with the tube portions of said fin members for supporting said pipe in spaced relation to the walls of said one of said plurality of refrigerant passages, and said means cooperating with the crevice in said pipe to provide a plurality of spaced apart openings throughout the length of said pipe for discharging liquid refrigerant into said one refrigerant passage at a plurality of spaced points.

3. A cooling element for a refrigerating system comprising in combination, a plurality of unidirectionally nested members secured together to form a unitary structure, said members including fin portions having tube portions formed integral therewith and telescoped together to provide a plurality of refrigerant passages through the structure, means for connecting an end of one of said passages to an end of another of said passages at one end of the structure, means for connecting the other end of said one of said passages with an end of still another of said passages at the other end of the structure, said last-named means forming a header communicating with all of said plurality of refrigerant passages and being provided with a refrigerant outlet connection, a pipe within one of said refrigerant passages and provided with a plurality of outlets for distributing liquid refrigerant at a plurality of points along the length of the said one passage, a liquid refrigerant inlet connection for said cooling element, and a refrigerant passage communicating with said pipe and with said liquid refrigerant inlet connection for conveying incoming liquid refrigerant to said element directly to said pipe.

4. A cooling element for a refrigerating system comprising in combination, a plurality of unidirectionally nested members secured together to form a unitary structure, said members including fin portions having tube portions formed integral therewith and telescoped together to provide a plurality of refrigerant passages through the structure, means for connecting an end of one of said passages to an end of another of said passages at one end of the structure, means for connecting the other end of said one of said passages with an end of still another of said passages at the other end of the structure, said last-named means forming a header communicating with all of said plurality of refrigerant passages and being provided with a refrigerant outlet connection, a pipe within one of said refrigerant passages and provided with a plurality of outlets for distributing liquid refrigerant at a plurality of points along the length of the said one passage, a liquid refrigerant inlet connection for said cooling element, a refrigerant passage communicating with said pipe and with said liquid refrigerant inlet connection for conveying incoming liquid refrigerant to said element directly to said pipe, and a conduit having one end thereof connected to the lower portion of said cooling element and having its other

end communicating with said liquid refrigerant inlet connection, said other end of said conduit being constructed and arranged to cause liquid refrigerant flowing into the cooling element to create a suction in the conduit for recirculating liquid refrigerant from one part of the cooling element to other parts thereof.

5. A cooling element for a refrigerating system comprising in combination, a plurality of 10 unidirectionally nested members secured together to form a unitary structure, said members including fin portions having tube portions formed integral therewith and telescoped together to provide a plurality of refrigerant passages 15 through the structure, means for connecting an end of one of said passages to an end of another of said passages at one end of the structure, means for connecting the other end of said one of said passages with an end of still another of 20 said passages at the other end of the structure, said last named means forming a header communicating with all of said plurality of refrigerant passages and being provided with a refrigerant outlet connection, a pipe within one of said 25 refrigerant passages and provided with a plurality of outlets for distributing liquid refrigerant at a plurality of points along the length of the said one passage, a liquid refrigerant inlet connection for said cooling element, a refrigerant 30 passage communicating with said pipe and with said liquid refrigerant inlet connection for conveying incoming liquid refrigerant to said element directly to said pipe, and a conduit having one end thereof connected to the lower portion of said header and having its other end disposed in the path of liquid refrigerant flowing into said inlet connection, said other end of said conduit being constructed and arranged to cause liquid refrigerant flowing into the cooling element to 40 create a suction in the conduit to thereby recirculate liquid refrigerant from one part of the cooling element to other parts thereof.

6. A cooling element for a refrigerating system comprising in combination, a plurality of unidirectionally nested members secured together to 45 form a unitary structure, said members including fin portions having tube portions formed integral therewith and telescoped together to provide a

plurality of refrigerant passages through the structure, means for connecting an end of one of said passages to an end of another of said passages at one end of the structure, means for connecting the other end of said one of said passages with an end of still another of said passages at the other end of the structure, said last named means forming a header communicating with all of said plurality of refrigerant passages and being provided with a refrigerant outlet connection, a pipe within one of said 10 refrigerant passages, means formed integral with the tube portions of said members for supporting said pipe in spaced relation to the walls of said one of said refrigerant passages, said pipe having a crevice 15 in its top surface and extending substantially throughout the length of the pipe, said means formed integral with the tube portions of said members cooperating with the crevice in said pipe to provide a plurality of spaced apart openings 20 throughout the length of said pipe for discharging liquid refrigerant into said one of said refrigerant passages at a plurality of spaced points, a liquid refrigerant inlet connection for said cooling element, and a refrigerant passage communicating with said pipe and with said liquid refrigerant inlet connection for conveying incoming liquid refrigerant to said element directly to said pipe.

7. A cooling element for a refrigerating system comprising in combination, a plurality of metal fin members each having a tube portion extending therefrom, said fin members being superimposed one upon the other with the tube portions thereof telescoped and secured together to provide a closed refrigerant passage extending transversely to the fin members, a pipe disposed within said refrigerant passage, said pipe having a crevice therein extending lengthwise thereof, means formed integral with certain of the tube portions of said fin members for supporting said pipe in spaced relation to the walls of said refrigerant passage, and said means cooperating with the crevice in said pipe to provide a plurality of spaced apart openings for discharging liquid refrigerant into said refrigerant passage at a plurality of points along the length thereof.

JOHN KARMAZIN.
